UNITED STATES PATENT OFFICE.

PROSPER OGER, OF ROUBAIX, FRANCE.

CARD CLOTHING FOR CARDING ENGINES.

Application filed July 18, 1921, Serial No. 485,734. Renewed June 17, 1925.

To all whom it may concern:

Be it known that I, PROSPER OGER, a subject of the King of Belgium, residing at Roubaix, in the Republic of France, have 5 invented new and useful Improvements in Card Clothing for Carding Engines, of which the following is a specification.

This invention relates to the card clothing employed for the rollers of carding engines, generally designated by the name of flyers and the function of which is, as is well known, to strip the cylinder of the carding engine.

In card clothing hitherto employed for 15 the flyers of carding engines, the setting of the clothings is effected parallel with the axis of the flyer, the hooks of the clothing being directed in planes at right angles to the axis of the flyer. These clothings, by 20 working between the clothings of the cylinder, remove more or less completely the waste and materials which accumulate between the clothings of the cylinder, but are unable to remove the waste and materials 25 which lodge between the teeth of the clothings of the cylinder, situated in the same plane. It therefore becomes necessary at certain times to stop the working of the machine in order to carry out a complete stripping of the cylinder.

The present invention has for its principal object to obviate this disadvantage, that is to say to obtain a more complete stripping of the clothings of the cylinder by 35 permitting the clothings of the flyer to exercise their action even between the teeth of the clothings of the cylinder situated in parallel planes at right angles to the axis of the cylinder.

With this object in view my invention 40 essentially consists in a special arrangement of the hooks of the clothing of the flyer whereby the ends of the hooks are caused to act between the teeth placed in the same 45 plane on the cylinder, as will be hereinafter fully described and pointed out in the appended claims.

Referring to the annexed drawing:

Fig. 1 shows diagrammatically the arrangement and mode of the setting employed hitherto for the clothing of the flyers and the cooperation of these clothings with those of the cylinder of the carding engine.

Fig. 1^a is a front view of a part of a clothing of the usual construction.

Fig. 1^b gives a section taken on line A—B and Fig. 1^c a section on line C—D in Fig. 1^a.

Fig. 2 and Fig. 3 are longitudinal sections of a flyer showing diagrammatically the arrangement of the hooks of the clothings according to the invention.

Fig. 2^a is a front view of a part of a clothing provided with the setting shown diagrammatically in Fig. 2.

Fig. 2^b is a section taken on line E—F and Fig. 2^c a section taken on line G—H in Fig. 2^a.

Figs. 4 and 5 are front elevations of flyers showing the clothing on the surface of 70 said flyers.

Figs. 6 and 7 show diagrammatically another mode of the setting which can be used in the arrangement shown in Figs. 2 to 5.

Fig. 6^a is a front view of a part of a clothing provided with the setting shown in Fig. 6.

Fig. 6^b is a section taken on line I—J and Fig. 6^c a section taken on line K—L in Fig. 6^a.

In the ordinary clothing for flyers of carding engines, the setting is effected, as is well known parallel with the axis of the flyer, or, in other words a plurality of wires (Fig. 1) provided with two branches *b* at 85 right angles with a central part *a* are fixed on or passed through a supporting material *p* (Figs. 1^a 1^b 1^c), such as leather for instance, in such a manner that the branches *b* project from the supporting material *p* 90 which is then placed on the surface of the flyer with the central part *a* of the wires 95 parallel with the axis of the flyer.

The projecting branches *b* form then hooks *b*¹ which are situated in planes parallel with each other and at right angles to the axis. The result is that the points or teeth of the hooks *b* act solely between the parallel rows *c* formed by the hooks of the clothing of the cylinder of the carding engine as shown diagrammatically in Fig. 1 (in which the points of the hooks of the clothing of the carding engine have been shown) but cannot exercise their action in the spaces *d* comprised between the successive points or teeth of the same row of the clothing of the cylinder.

This disadvantage is avoided, according to my invention by giving to the hooks *b*¹ a lateral inclination that is to say towards the right or towards the left, with respect to the axis of the flyer as is shown in Fig.

ures 2 and 3 which represent sections of the flyer *e* mounted on its shaft *f*. Under these conditions the inclined hooks *b*¹ penetrate into the spaces *d* (Fig. 1) of the clothing 5 of the cylinder of the carding engine and are able to remove the waste and the materials which accumulate during the working of the carding engine.

The two inclinations, to the right and to 10 the left may naturally be combined on the same flyer and the clothings may be advantageously arranged in the form of chevrons *g* and *h* adjacent to each other, as shown in Fig. 4 or again in the form of chevrons 15 leaving between them uncovered intervals *i* on the surface of the flyer as shown in Fig. 5.

Under these conditions, the lateral action, 20 due to the inclination becomes reinforced, the stripped material having a tendency to collect at the ends of the flyer. In practice, this action may be combined with a to and fro movement of the flyer, from left to right and from right to left.

25 The lateral inclination of the hooks *b*¹ can be obtained by aid of the usual setting as it is shown in Figs. 2^a 2^b and 2^c. In this case the central part *a* of the wire (Fig. 2^a) extends longitudinally in contact with the 30 back of the supporting material *p*, parallel to the axis of the flyer upon which the clothing is placed, and the branches *b* are passed through said supporting material as it is the case in Figs. 1^a 1^b 1^c but the hooks *b*¹ instead of being formed in the same planes 35 as the part *b*² of the branches *b* which passes through the supporting material *p* and at right angles to the axis of the flyer are deflected laterally at *b*³ as it will appear from 40 a comparison of Figs. 2^a 2^b and 2^c in such a manner that the points or teeth of the hooks end in planes at right angles to the axis of the flyer but parallel to the planes containing the part *b*² of the branches passing through the supporting material.

45 The same result however can also be obtained with the form of hooked wires shown in Figs. 1^a 1^b 1^c, that is with the usual form of hooked wires by adopting the setting 50 shown diagrammatically in Figs. 6 and 7 which is effected at a suitable angle relatively to the axis of the flyer so that the teeth of the clothings hooked in the ordinary way are no longer situated in planes 55 at right angles to the axis of the flyer but rather in oblique planes parallel with each

other. This mode of setting is further illustrated in Figs. 6^a, 6^b and 6^c. As it will appear from a comparison of the said figures, the central part *a* of the wire is again placed on the back of the supporting material *p* but the branches *b* are passed through said supporting material on two parallel lines traced at different levels on the supporting material in such a manner 65 that the hooks *b*¹ are directed laterally although being formed at right angles to the central part *a* just like in the case shown in Figs. 1^a 1^b 1^c.

It should be noted that the arrangement 70 described might be also carried out by means of two cylinders covered with a strip of clothing forming very pronounced spirals, one covering running towards the left and the other towards the right, and further 75 that the arrangement may also be combined with the ordinary system of setting, the same cylinder or flyer being provided on its periphery with parts of clothing set in the ordinary way (Figs. 1^a 1^b, 1^c) and parts 80 set towards the left and right (Figs. 2 and 3) according to the effect desired to be obtained.

What I claim is:

1. Card clothing for fancy rollers of carding engines in which the teeth of the rows running perpendicularly to the lateral edges of the fabric are inclined toward one of the said edges, whereby the said teeth are adapted to act between the teeth of the clothing 90 of the main cylinder which are situated in parallel planes at right angles to the axis of the main cylinder of the carding engine.

2. In combination with a fancy roller of 95 a carding engine, a card clothing covering the said fancy roller, the said clothing comprising rows of teeth, the points of the said teeth being inclined laterally in the longitudinal diametral planes of the fancy roller containing the said rows of teeth, whereby the said teeth are adapted to act between the teeth of the clothing of the main cylinder which are situated in planes parallel to each other but at right angles to the axis of the main cylinder of the carding engine.

100 In testimony whereof I have signed my name to this specification in the presence of two subscribing witnesses.

PROSPER OGER.
